CLAIM

The ornamental design for a sports video camera, as shown and described.

DESCRIPTION

FIG. 1 is a front, top, and left-side perspective view of a first embodiment of a sports video camera;

FIG. 2 is a front-elevational view thereof;

FIG. 3 is a rear-elevational view thereof;

FIG. 4 is a left-elevational view thereof;

FIG. 5 is a right-elevational view thereof;

FIG. 6 is a top-plan view thereof; and,

FIG. 7 is a bottom-plan view thereof.

The broken lines shown in the drawings are for illustrative purposes only and form no part of the claimed design. The surface shading, if any, illustrated in the drawings is provided merely to highlight the contour of the design; it is not intended to be illustrative of texture or gloss.
